UNITED STATES PATENT OFFICE.

PALMER COX, OF NEW YORK, N. Y.

DESIGN FOR A HANDKERCHIEF.

SPECIFICATION forming part of Design No. 23,434, dated July 10, 1894.

Application filed February 19, 1894. Serial No. 500,795. Term of patent 14 years.

To all whom it may concern:

Be it known that I, PALMER COX, a citizen of the United States, and a resident of the city, county, and State of New York, have invented and produced a new and original Design for a Handkerchief or Similar Article of Textile Fabric, of which the following is a full, clear, and exact specification, reference being had to the drawing forming part thereof.

10 The object of my invention is to produce a design such as is not only new and original but also has a pleasing effect to the eye which is peculiar to itself, thus being attractive and popular.

15 My design as shown in the drawing is produced on woolen, silk, cotton or other fabrics. The drawing represents a handkerchief or similar article on which is shown my design.

20 The leading feature of this design consists in the figure of a Chinese Brownie which falls entirely within a square having his head in one angle and both feet in another. The center of this square is the center of the handkerchief, while it is arranged so as to present

25 a side toward each angle of the handkerchief. On one border of the handkerchief, above the Chinese Brownie and at right angles to him, appears a Japanese Brownie standing guard. On the border, beneath the Chinese Brownie

30 and at right angles to him appears a Jockey Brownie with whip in hand, as though awaiting the orders of the Royal Brownie who appears on the border to the right of the Chinese Brownie and at right angles to the Jockey Brownie. On the border to the left of the Chinese Brownie and at right angles to the Jockey Brownie appears an Egyptian Brownie with a wondering countenance. On the same border there appears inverted the figure of a Frenchman Brownie who when the handkerchief is turned is found to be eyeing the Japanese Brownie with respect to whom he is arranged at right angles. On the border with the Royal Brownie there appears inverted the figure of a Student Brownie with a book under his arm who, when the handkerchief is turned is found to be at right angles to the Japanese Brownie.

It is evident that if the leading feature of my design is dispensed with there will still remain in the figures on the border viewed with respect to each other an independent feature of my design.

Some of the figures are drawn to represent the characteristic dress of a peculiar country, thus serving to instruct the young while the design affords pleasure and amusement to both young and old.

I claim—

1. The design for a handkerchief or similar article substantially as herein shown and described.
2. In the design for a handkerchief or similar article substantially as herein shown and described, the border.

PALMER COX.
